UNITED STATES PATENT OFFICE.

GEORGE MAXIME CARPENTIER, OF NEW YORK, N. Y.

PROCESS OF PRODUCING A PHOTOGRAPHIC REPRODUCTION FOR USE IN MAKING BAS-RELIEF.

1,087,725. To *Specification of Letters Patent* to *Patented Feb. 17, 1914.*

Application filed December 20, 1911. Serial No. 666,911.

To all whom it may concern:

Be it known that I, GEORGE M. CARPENTIER, a citizen of the United States, and a resident of the city of New York, borough of Manhattan, in the county and State of New York, have invented a new and Improved Process of Producing a Photographic Reproduction for Use in Making Bas-Relief, of which the following is a full, clear, and exact description.

This invention relates to a new and improved process for producing photographic reproductions in relief of designs, paintings, engravings or photographs of any description with absolute fidelity of form and in any given size of the objects or figures the artist intended to represent.

The photographic reproductions produced by this process are suitable for use in the execution in relief, of portraits, mural or ceiling decorations, for forming bas-reliefs, church memorials, inscriptions, etc. From the photographic reproductions can be made casts in plaster or in metal or they may if desired be coated by a galvanic deposition of copper or silver.

For the purpose of explaining the invention, the same will be described with reference to the accompanying drawings, in which—

Figure 1 represents an object or picture to be reproduced in accordance with my invention. Fig. 2 represents a negative of such object or picture, the size desired for the finished plate. Fig. 3 represents a positive or transparency made from the negative shown in Fig. 2. Fig. 4 represents a sectional view of a composite plate formed by the positive and negative indicated in Figs. 2 and 3. Fig. 5 indicates an enlarged positive print taken from the said composite plate. Fig. 6 represents a negative of said enlarged print, the negative being of the size desired for the finished plate. Fig. 7 represents a transparency made from the negative shown in Fig. 6. Fig. 8 represents a sectional view of the molding plate with the bichromated gelatin film thereon. Fig. 9 is a similar view of a molding plate having a layer of plain gelatin beneath the bichromated gelatin layer, and Fig. 10 is a sectional view of the finished molding plate on an enlarged scale.

The object or picture to be reproduced indicated at A in Fig. 1 is to be examined for

possible defects, etc., which, if left, would mar the appearance of the finished plate. I take of this a negative B, Fig. 2 the size the plate is desired to be. If the object or picture is colored, I use an orthochromatic plate with a screen suitable to give me a negative with the color values as near as possible. This negative must be sharp and well contrasted and nevertheless give all the details of the picture. When the negative is finished and satisfactory, I place it in a printing frame in contact with an unexposed plate, and by artificial light give a very short exposure so as to obtain an attenuated positive or transparency. When this transparency C, Fig. 3 has been developed, fixed and washed, I place in the washing water with it the negative, and after one or two minutes bring both plates together, film against film, under water and place them in perfect register. D, Fig. 3, represents the composite plate thus formed. I hold them firmly in that position and let them set. This cemented plate D is then to be placed in an enlarging camera, and a positive print E, Fig. 5, double its size, is to be taken on developing paper. The finished print is now to be placed side by side with the object or picture to be reproduced, and with brush or pencil or both, I go over all that is background and cover it with a tint of black proportionate to the relief I intend to give the figures on the picture or which I judge will produce the best effect. The darker the background, the higher relief will have the figure next to it, and inversely the figure will be depressed in the neighborhood of light colored background. When all that is to be background has been treated, the picture itself has to be examined and tinted and touched up either with pencil or mainly with very thin transparent water colors ranging from white to crimson. This touching up for relief has to be done very sparingly and with the greatest of care. In fact, this part of the work requires a great deal of skill and artistic taste, and if one is not proficient in that line, he would better have it done by some artist who has experience in retouching high-class photographs. Of this now finished print, I take a negative F, Fig. 6, of the exact size the finished plate is to be, and this negative must be of a moderate density, so as to allow full play to the light going through it in the subsequent operation.

This treatment of the picture applies in all cases when the relief-to-be appears on the picture of a lighter color than the rest, as for instance for the portrait of an old lady with white hair, and dressed in a white or light colored garment, or in the case of a building of white stone or marble; but in the reverse conditions, that of a building of brown stone, or the portrait of a young person with dark hair and wearing dresses of a dark material, it is obvious that the treatment of the picture is to be reversed, the background being tinted in light color or even white, either in whole or in part, as the case may present itself, and the objects forming the picture will have to be treated inversely also, and in that case, instead of taking a negative of the picture, I take a reversed negative of it, either by reversing the plate in the plate holder or by using a prism in front of the lens.

I have now to describe how I make the molding plate. It has been found that a gelatin film impregnated with suitable chemicals, such as potassium bichromate and sugar, when exposed to the action of sunlight passing through a photographic transparency, will be eaten into proportionately to the lights and shadows of said transparency, so as to produce a grain or pitted effect in the film. Advantage is taken of this action in the production of the molding plate. I take of Nelson's No. 2, or of Coignet's gold lable gelatin one pound, soak it in eighty ounces of water, to which I add about two ounces of white candy sugar, and let this soak for forty-eight hours. After that time, the gelatin will have absorbed the whole of the water, and the sugar will have dissolved. I place the receptacle containing it in a water bath at a temperature of 120° Fahrenheit. When melted, I divide it in two parts, each in a separate vessel. Now I take half-an-ounce of talcum powder and triturate it in a mortar with water to the consistency of a thick paste, and I add to it enough of the dissolved and warm gelatin to make thin enough to be strained through muslin, and mix it up thoroughly with the gelatin contained in one of the vessels. To this same vessel, I add sixty grains of potassium bichromate, and stir it up until dissolved. I take glass plates previously cleaned and place them on a slab of plate glass carefully leveled. Now I take the vessel containing the plain gelatin and pour over half of the plates enough gelatin to cover them over with pretty thick coating, conducting the fluid gelatin around the edges and corners with a glass rod. Now when this coating of plain gelatin has set, I take the vessel containing the pigmented and bichromated gelatin and pour over these plates as much as they can take without running over the edges and all over the

plain plates as well. So I have two grades of plates, one having only one layer of bichromated gelatin, and the other with an under coating of plain gelatin. The first grade is to be used for plates having small figures, and the second grade is to be used in all cases where the figures are large enough to stand a high relief, this relief depending upon the amount of plain gelatin underlying the bichromated coating. I leave those plates to set thoroughly on the leveled slab, and put them on edge in a rack to dry. When dry, they can be wrapped up in black or red tissue paper, put up in a box, and placed in a dry place, they will keep for several months ready for use. These two grades of plates are shown in section in Figs. 8 and 9. In these figures, G represents the glass plate, H, Fig. 8, the layer of bichromated gelatin, and in Fig. 9, H indicates the layer of bichromated gelatin, and I the layer of plain gelatin. Now I have the negative F, Fig. 6, I made of the light relief picture, and make with it, by contact in the printing frame, a transparency J, Fig. 7, which, when finished and dry, I place in a printing frame with one of the molding plates over it. If my picture is of the dark relief sort, I use the reversed negative instead. In any case, I expose my plates in the direct rays of the sun for fifteen minutes in summer, and for sixty minutes in winter, varying the time of exposure according to the month of the year, having those two extremes as a guide. I then take the exposed molding plate and place it in a tray where water is running, and leave it there until I am satisfied that the water is no longer stained by the soluble bichromate.

Fig. 10 shows the finished molding plate in which G indicates the glass plate and H the layer of bichromated gelatin having the figure or other object K in relief. After draining, the plate may be coated with a metallic film in any suitable manner.

While I have shown two embodiments of my invention, I do not wish to be limited to the specific details thereof, but desire to be protected in various changes, modifications and alterations which may come within the scope of the appended claims.

Having thus described my invention, I claim as new and desire to secure by Letters Patent:—

1. The process of producing a photographic reproduction for use in forming a bas-relief, which consists in making a composite formed of a negative and a positive photographic reproduction of the object or picture to be simulated, taking an enlargement of the said composite, accentuating the lights and shadows in the enlargement, forming a negative from the finished enlargement the exact size desired in the fin-

ished article, making a transparency from said negative, transmitting light through this transparency onto a film impregnated with chemicals to render said film insoluble 5 proportionately to the lights and shadows of said transparency, and washing said film to remove the soluble matter.

2. The process of producing a photographic reproduction for use in forming a 10 bas-relief, which consists in making a composite formed of a negative and positive photographic reproduction of the picture or object to be reproduced, taking an enlarged positive on paper from the said composite, accentuating the lights and shadows on said positive, making a negative from said positive, making a photographic transparency from said negative, subjecting a 15 gelatin film impregnated with potassium bichromate and sugar to the action of light passing through said transparency, and washing the exposed film.

3. The process of producing a photographic reproduction for use in forming a 20 bas-relief, which consists in making a composite negative and positive photographic reproduction of the object or picture to be reproduced, making an enlargement of said photographic reproduction, accentuating 25 the lights and shadows in said enlargement, producing a negative from said enlargement, making a photographic transparency from said negative, exposing a film having 30 a layer of plain gelatin, superimposed by a layer of bichromated gelatin, to the action of rays of light passing through said transparency, and washing the exposed 35 film.

4. The process of producing a photographic reproduction for use in forming a 40

bas-relief, which consists in making a negative of the object or picture which it is desired to reproduce, making a positive or transparency from said negative, placing said positive and negative in register, making an enlargement of the composite formed by the positive and negative, accentuating the lights and shadows in said enlargement, making a negative of said enlargement, making a transparency from said negative, 45 subjecting a bichromated gelatin film to the action of rays of light passing through said transparency, and washing the exposed film.

5. The process of producing a photographic reproduction for use in forming a 50 bas-relief, which consists in taking a negative of the object or picture to be reproduced of the size the finished article is desired to be, making an attenuated positive or transparency from said negative, bringing the 55 positive and negative films into register under water, placing the composite plate formed by the negative and positive in an enlarging camera and making a positive print double its size on developing paper, 60 accentuating the lights and shadows on said positive print, taking a negative of the finished print of the exact size the finished plate is to be, printing a transparency from said negative, exposing a bichromated gelatin 65 film to the action of rays of light passing through said transparency, and washing the exposed film.

In testimony whereof I have signed my name to this specification in the presence of 70 two subscribing witnesses.

GEORGE MAXIME CARPENTIER.
